[57] CLAIM

The ornamental design for a disposable staple cartridge for linear closure surgical stapler, as shown and described.

DESCRIPTION

FIG. 1 is a perspective view of a disposable staple cartridge for a linear closure surgical stapler showing my new design;

FIG. 2 is a perspective view as seen from the side opposite FIG. 1;

FIG. 3 is a side elevation;

FIG. 4 is an end elevation as seen from the right of FIG. 3;

FIG. 5 is an end elevation as seen from the left of FIG. 3;

FIG. 6 is a side elevation as seen from the opposite side of FIG. 3;

FIG. 7 is a bottom plan view; and

FIG. 8 is a top plan view.
